(57) **CLAIM**

The ornamental design for a fairing for motorcycles as shown and described.

DESCRIPTION

1.1 is a front perspective view of a fairing for motorcycles;

1.2 is a front view thereof;

1.3 is another front perspective view thereof;

1.4 is a side view thereof;

1.5 is an opposite side view thereof;

1.6 is a top view thereof; and

1.7 is a bottom view thereof; and

1.8 is a rear view thereof.

The broken lines illustrate portions of the fairing for motorcycles which form no part of the claimed design.
